UNITED STATES PATENT OFFICE.

ODELON JOSEPH LA BAUVE, OF EDNA, TEXAS.

CRATE.

No. 818,697.

Specification of Letters Patent.

Patented April 24, 1906.

Application filed August 22, 1905. Serial No. 275,261.

To all whom it may concern:

Be it known that I, ODELON JOSEPH LA BAUVE, a citizen of the United States, residing at Edna, in the county of Jackson and State of Texas, have invented new and useful Improvements in Crates, of which the following is a specification.

My invention is a crate or coop, and more particularly the kind which can be knocked down and folded.

The object of the invention is to provide a crate of this kind embodying certain novel features of construction hereinafter described and claimed.

15 In the accompanying drawings, Figure 1 is an elevation of a crate constructed in accordance with my invention. Fig. 2 is a horizontal section on the line 2-2 of Fig. 1. Fig. 3 is a top plan view. Fig. 4 is an elevation showing 20 the crate folded. Fig. 5 is an elevation of a modification, and Fig. 6 is a top plan view thereof. Fig. 7 is a vertical sectional view on the line 7-7 of Fig. 6.

Referring specifically to the drawings, 10 25 denotes the floor of the crate. At each corner of the floor are secured angular pieces which extend around the corners, as at 11 and 12, and above the floor a short distance and form a support for the side and end walls 30 of the crate. The side walls are made of wire-netting 13, which is secured in a metal frame comprising top, bottom, and end rods 14, 15, and 16, respectively. The end walls are similarly constructed, the top, bottom, and 35 end rods of the frame being indicated at 17, 18, and 19, respectively. These rods are connected by T-couplings 20 or in any other suitable manner. Instead of the wire-netting the side and end walls may be slatted.

40 The rods 15 are pivotally connected to the parts 11 of the corner-pieces, so that the side walls can be folded inwardly upon the floor. This connection is made by bolts 21, extending through the parts 11 and screwed into the 45 T-couplings at the ends of the rods 15. The end walls are connected to the parts 12 of the corner-pieces in the same manner as the side walls and fold inwardly upon the top of the side walls when the latter are folded. The 50 pivot-bolts 22, connecting the end walls to

the corner-pieces, are located above the bolts 21 a sufficient distance to permit the walls to fold, as stated. The top of the crate is constructed substantially the same as the side and end walls, the rods 23 comprising the 55 frame being joined by L-couplings 24 or other suitable means.

Means for holding the crate in set-up position comprises pins 25, rising from the coupling 20 at the top of the end walls and extending through holes in the couplings 24 when the top is on the crate. Locking-keys 26 are extended through the pins, whereby the top is securely held in position. Pins 27 also extend inwardly from the couplings 20 at the 65 top of the end walls and enter the couplings 20 at the top of the side walls, whereby the latter are prevented from collapsing when the crate is set up.

A crate constructed as herein described 70 can be cheaply produced, and it is strong and durable and will withstand rough handling.

In the modification shown in Figs. 5 to 7 a wooden crate is shown. The side and end walls comprise top and bottom bars 28 and 75 29, respectively, connected by slats 30. Instead of slats a wire-netting may be used. The walls are pivotally connected to the corner-pieces to fold in the same manner as heretofore described. Straps 31 are secured to 80 the bottom bars 29, the outer ends of said straps being formed with threaded stems 32, which extend through the corner-pieces and are secured by nuts 33. The top of this modified form of crate comprises end bars 34, 85 connected by cross-slats 35. The slats project beyond the end bars, so as to rest on top of the bars 28 of the side walls when the top is on the crate, the end bars 34 fitting snugly against the inner walls of the top bars 28 and preventing said side walls from folding inwardly. The parts are also connected by hasps 36 or other suitable fastening means to prevent collapse when the crate is set up.

Having thus described my invention, what 95 is claimed as new, and desired to be secured by Letters Patent, is—

A crate comprising a bottom, folding side walls having sockets at the top, folding end walls carrying projecting pins entering the 100

aforesaid sockets when the walls are in upright position, pins extending upwardly from the top of the end walls, a top having vertical openings therein to receive the last-mentioned pins, and keys extending through the projecting ends of said pins.

5 In testimony whereof I have signed my

name to this specification in the presence of two subscribing witnesses.

ODELON JOSEPH LA BAUVE.
